CHRISTOPHER S. REAMY, OF LOS ANGELES, CALIFORNIA.

SCREW GRIPPER AND DRIVER.

1,075,225.

Specification of Letters Patent.

Patented Oct. 7, 1913.

Application filed January 13, 1913. Serial No. 741,889.

To all whom it may concern:

Be it known that I, CHRISTOPHER S. REAMY, a citizen of the United States of America, residing at Los Angeles, in the county of Los Angeles, State of California, have invented a certain new and useful Screw Gripper and Driver; and I do hereby declare the following to be a full, clear, and exact description of the invention, such as will enable others skilled in the art to which it appertains to make and use the same.

This invention relates to screw gripper and driver, and it may be said to consist in the provision of the novel and advantageous features and in the novel and improved construction, arrangement, and combination of parts in the device as will be apparent from the description and claim which follow hereinafter.

One object of the invention is to provide a novel and improved device which in practice is adapted to act effectively to automatically grip the screws so that they are firmly held by the device and need not be held by the fingers of the user of the device.

A further object of the invention is to provide a novel and improved device which is adapted to act effectively to grip the screws when the latter are being driven to place or when they are being withdrawn after being driven to place.

Further objects of the invention are to provide a novel and improved device of the class specified, which is simple in construction, strong and durable, attractive in appearance, cheap to manufacture, effective in use, and in which the parts are adapted to be easily and quickly assembled.

Further objects and the advantages of the invention will be apparent to those skilled in the art from a consideration of the following description of the preferred form of construction embodying the invention, taken in connection with the accompanying drawings in which—

Figure 1 is an elevational view of the device applied to a screw; Fig. 2 is a central longitudinal sectional view taken on the line 2—2 of Fig. 4; Fig. 3 is a view similar to Fig. 2 with the movable parts in changed position; Fig. 4 is a plan view of the outer portion of the device; Fig. 5 is a cross-sectional view taken on the line 5—5 of Fig. 2; and Fig. 6 is a broken elevational view of the device at right angles to that shown in Fig. 1.

The hollow casing 7, preferably cylindrical in form, has one end portion thereof formed to provide substantially oppositely disposed converging portions or shoulders 8. 60 To the other end portion of the casing 7 is secured a handle 9 which is provided with a substantially central longitudinal opening 10 in alignment with the opening in the casing 7 and which has an annular shoulder 65 11 against which the end of the casing 7 abuts. A ferrule 12 may be fitted against the casing 7 and over the inner end portion of the handle 9.

Within the casing 7 is slidably arranged 70 a rod 13 which extends outwardly through the opening 10 in the handle 9. In the end portion of the rod 13 within the casing 7 are securely fitted one end portion of fingers 14 which have the other end portion adapted 75 to be normally sprung apart, see Fig. 2. The fingers 14 have thereon intermediate of their ends, diverging portions or shoulders 15 which are adapted to coact with the shoulders 8 on the casing 7 to bring together 80 the lower end portion of the fingers 14 as seen in Fig. 3.

To limit the inward and outward movement of the rod 13 a projection 16 is provided on the end of the casing 7 within the 85 handle 9 which projection is adapted to engage with the end walls of a slot or cutaway portion 17 formed in the rod 13.

From the foregoing the advantages and manner of use of the device will be evident 90 to those skilled in the art, it being understood that when the parts are in the position shown in Fig. 2, the rod 13 may be moved inwardly by pressing the outer end thereof with the fingers or against a wall or surface 95 to have the parts moved to the position shown in Fig. 3, whereupon the free end portion of the fingers 14 may be fitted in the slot 18 in the screw 19 and the device may then be pressed against the screw or the 100 screw may be pressed against the device to have the fingers 14 spring apart and firmly grip the screw.

While one form of construction embodying the invention has been particularly illustrated and described there are many changes and modifications thereof that will readily occur to those skilled in the art, wherefore the right is reserved to all such changes and modifications as do not depart from the 110 spirit and scope of the invention as defined in the appended claim.

2

I claim:

A device of the class specified, comprising a hollow casing having one end portion thereof provided with shoulders, a handle secured to the other end portion of the casing and provided with an opening substantially in alinement with the casing, a rod slidably arranged in the casing and adapted to extend through the opening in the handle, fingers having one end portion thereof secured to the rod within the casing and having the other end portion thereof adapted to normally spring apart, said fingers provided with shoulders adapted to co-act with

the shoulders on the casing to move the fingers toward each other, and a projection on the casing adapted to limit the movement of the rod.

In testimony whereof, I have signed my name to this specification in the presence of two subscribing witnesses at Los Angeles, county of Los Angeles, State of California, this 4th day of January A. D. 1913.

CHRISTOPHER S. REAMY.
